UNITED STATES PATENT OFFICE.

JOHN W. CLANTON AND ARTHUR W. BLANCHARD, OF PAYETTE, IDAHO, ASSIGNEES OF
ONE-THIRD TO GEORGE W. CLANTON, OF PAYETTE, IDAHO.

HYDROMOTOR.

Application filed September 2, 1922. Serial No. 525,948.

To all whom it may concern:

Be it known that we, JOHN W. CLANTON and ARTHUR W. BLANCHARD, citizens of the United States, and residents of Payette, and county of Payette, and State of Idaho, have invented certain new and useful Improvements in Hydromotors, of which the following is a specification.

This invention relates to motors which use flowing water as a source of power.

Briefly stated an important object of this invention is to provide a water motor wherein the wheel is so arranged that its blades are successively presented to the flowing water so that the wheel will be caused to rotate and drive a suitable mechanism, at any desired point.

Further the invention forming the subject matter of this application aims to provide novel means whereby the flow of water will be deflected so that the wheel may stop.

A further object is to provide a water motor of a character specified which is of highly simplified construction, durable in use and cheap to manufacture.

Other objects and advantages of the invention will be apparent during the course of the following description.

In the accompanying drawing forming a part of this application and in which like numerals are employed to designate like parts throughout the same,

Figure 1 is a detail longitudinal section through the motor,

Figure 2 is a fragmentary plan view of the motor,

Figure 3 is a vertical transverse section taken on line 3—3 of Figure 1, and

Figure 4 is a fragmentary side elevation of the motor.

In the drawing wherein for the purpose of illustration is shown a preferred embodiment of the invention, the numeral 5 designates a float or barge adapted to float upon the water and suitable means may of course be employed for securing the barge in the desired position. As illustrated in Figures 2 and 3 the opposite sides of the barge are provided with beams 6 which terminate in advance of the barge and are joined by a cross member 7. The pair of spaced parallel beams 6 have their extended portions provided with U-bolts 10 which carry bearings 11. The bearings 11 of which there are two 55 rotatably support the axle 12 of an air-tight

drum 13, the said drum being rotatably supported and confined between the parallel beams 6.

The drum 13, which is of cylindrical formation, has internal reinforcing rods 14 of annular formation and these rods effectively brace and strengthen the drum. The rods 14 which are of annular formation are T-shaped in cross section.

Figure 1 illustrates that a plurality of 65 paddles or blades 20 are hingedly connected to the drum.

The flow of water may be deflected when desired by means of a segmental hood 60 which may be dropped in front of the blades 70 and as illustrated in Figure 4 the transversely curved hood is provided with segmental walls 61 rotatably connected to the end portions of the axle 12. Fig. 1 illustrates that the transversely curved hood 60 is provided with transversely extending reinforcing bars 96 through which a longitudinally extending rod 62 is connected and as illustrated in Figure 3 a link 64 is connected at one end to the rod 62. The other end of 80 the link 64 is connected to an actuating lever 65 by means of which the hood may be adjusted when necessary. It will be observed that the lever 65 has pivotal connection intermediate its ends with the link 64 and is 85 pivotally connected at its forward end to a stub shaft 131 mounted on brackets 132. The brackets 132 are secured in position by bolts similar to those which secure the bearings 44 in place. The air tight drum 13 is 90 sealed of course and the shaft 12 is provided with a longitudinally extending duct or passage 70 closed by means of a valve 71 and a suitable cap 73 may be threaded onto the shaft 12 so as to cover the valve 71. 95

With reference to the foregoing description, taken in connection with the accompanying drawing, it will be apparent that a water motor constructed in accordance with this invention may be readily placed in the 100 water and will easily operate a pump or the like and the motor may be operated without the exercise of unusual skill or effort.

As illustrated in Figures 2 and 4 the end walls 30 of the drum are formed with annular extensions 31. The annular extensions 31 arranged at the ends of the drum are provided with inwardly directed flanges 32 which extend beyond the outer longitudinal edges of the blades 20. Also the annular 110

extensions 31 are provided on their inner sides with stop flanges 33 which form abutments for the blades 20 when the latter are moved to their operative positions as illustrated in Figure 2.

It will be observed that as the wheel rotates the blades will successively assume their operative positions and engage the inwardly directed stop flanges or abutments 33. When the blades assume their proper positions the water will contact with the same and thereby revolve the wheel and the belts 40 trained about the pulleys 41 at the ends of the drum will be operated for turning a pair of drums 42, the said drums being connected to a shaft 43.

The shaft 43 is supported by bearings 44 and the shaft 43 is provided with a crank 46 which may be connected to a pump mounted on the stand 48 or if desired the crank may be connected to any other suitable mechanism. However, it is preferred to operate the pump which in turn will pump water for irrigation or other purposes.

The driving connection between the several pairs of pulleys may be by means of a belt as illustrated, a chain or in fact a series of gears may be employed.

However when belts are employed, belt tensioning levers 80 provided with rollers 81 may be employed and in that case springs 83 will shift the levers 80. A suitable adjusting stem or shaft 84 may be threaded through each beam and employed as a means to vary the tension of the coiled springs 83.

It is to be understood that the form of the invention herewith shown and described is to be taken as a preferred example of the same and that such minor changes in arrangement and construction of parts may be made as will remain within the spirit of the invention and the scope of what is claimed.

Having thus described the invention, what is claimed is:—

1. A water motor comprising a float having a pair of beams extended beyond the ends thereof, an axle carried by said beams, a wheel rotatably carried by said axle and having end walls provided with stops, paddles hinged to the wheel and adapted to engage said stops, a transversely curved hood arranged about said wheel and having segmental end walls rotatably connected to said axle, and an adjusting link connected to said hood.

2. A water motor comprising a float having a pair of beams extended beyond the ends thereof, an axle carried by said beams, a wheel rotatably carried by said axle and having end walls provided with stops, paddles hinged to the wheel and adapted to engage said stops, a transversely curved hood

arranged about said wheel and having segmental end walls rotatably connected to said axle, an adjusting link connected to said hood, power transmitting devices arranged at the ends of the wheel and being connected thereto, and a second set of power transmitting devices arranged upon the float and operatively connected to the first named power transmitting devices.

3. A water motor comprising a float, an axle carried thereby, a wheel mounted upon the axle and having end walls provided with annular extensions, stop flanges carried by said extensions, paddles hinged to the wheel at the surface thereof and adapted to engage said stop flanges, said wheel being in the nature of a hollow air-tight drum, a transversely curved hood arranged about said wheel and having end walls rotatably connected to said axle, and means whereby to position said hood in its operative or inoperative position.

4. A water motor comprising a float, a pair of beams carried by the sides of the float and extending from one end of the same, a wheel rotatably carried by said beams and having end walls provided with annular extensions, the edges of which are extended inwardly, stop flanges carried by the inner sides of said extensions, paddles hinged to the periphery of the wheel and adapted to engage said stop flanges, power transmitting means connected to the ends of said wheel, said wheel being in the nature of a hollow air-tight drum, and a transversely curved hood arranged about said wheel and having segmental end walls rotatably supported and arranged at the ends of the wheel.

5. A water motor comprising a float having a pair of parallel beams extending beyond one end of the float, a wheel having an axle rotatably connected to said beams, the end walls of said wheel being formed with annular extensions, the edge portions of which are extended inwardly, and paddles hinged to said wheel, stop flanges carried by said extensions and engaged by said paddles, pulleys secured to the ends of said wheel, power transmitting members trained about said pulleys, a second pair of pulleys connected to said power transmitting members, a crank shaft having connection with the second named pulleys, a hood having segmental end walls rotatably connected to said axle, a link connected to said hood, and a lever connected to said shaft and having connection with said link and forming a means whereby to control the link and the hood.

JOHN W. CLANTON.
ARTHUR W. BLANCHARD.
